UNITED STATES PATENT OFFICE.

LOUIS G. BOSTEDO, OF CHICAGO, ILLINOIS.

TERMINAL FOR PNEUMATIC-DESPATCH-TUBE SYSTEMS.

SPECIFICATION forming part of Letters Patent No. 597,138, dated January 11, 1898.

Application filed May 17, 1897. Serial No. 636,975. (No model.)

To all whom it may concern:

Be it known that I, LOUIS G. BOSTEDO, of Chicago, Illinois, have invented certain new and useful Improvements in Terminals for 5 Pneumatic-Despatch-Tube Systems, of which the following is a specification.

This invention relates to pneumatic-despatch-tube systems, and more particularly to that part of the system known as a "receiving terminal," and has for its object to provide means for automatically controlling the air-pressure, so that when the carrier reaches the terminal it will be discharged therefrom with certainty and with a minimum waste of the 15 propelling power.

A further object of the invention is to employ the pressure due to air-compression by the carrier directly upon the piston which actuates the gate or valve, whereby a quicker 20 action is obtained than where the carrier-pressure is used to operate valves which in turn control a pressure from other sources than the carrier-pressure for acting upon the piston which operates the gate.

25 In the accompanying drawings, Figure 1 is a plan view of a structure embodying my invention. Fig. 2 is a side elevation of the same. Fig. 3 is a plan section of the sliding gate or valve and its associated parts. Fig. 30 4 is a side elevation of the same. Fig. 5 is an enlarged view, partly broken away, of a portion of Fig. 1, showing the end gate or valve.

In the said drawings is shown an apparatus 35 of the exhaust type, in which A represents the pump or fan connection, and B the terminal tube, the end of which is adapted to be closed by a gate or valve C, hinged below to the tube B and inclined, when closed, in 40 the direction of travel of the carrier. This door is held closed and is automatically returned to its closed position by a weak spring c, bearing on its under side, as shown in Fig. 2.

D indicates a sliding gate or valve moving 45 in ways d across the tube B at a point thereof near the exhaust connection A and connected by a piston-rod e with a piston E, mounted in a cylinder E². From the outer end of the cylinder E² a tube E', provided with a regulating-valve e', extends to and communicates 50 with the main tube B near the delivery end thereof. The inner end of the cylinder is

provided with an air-inlet aperture e², communicating with the atmosphere. It will be noted that the sliding gate or valve D is of 55 considerable width or thickness, thus presenting an area exposed to the exhaust action of sufficient dimension to cause said exhaust to tend to draw said gate inward across the tube B to close the same. 60

F indicates a by-pass extending from a point in the tube B near the outer or discharge side of the gate D to a point near the delivery end of said tube and provided with a regulating-valve f. 65

Ways G are provided to receive the carrier as it is discharged from the tube B, and there is provided on the upper or inner side of the door or gate C a corresponding way G', forming a continuation of the central way G when 70 said door is lowered, as hereinafter described.

The apparatus thus organized operates in the following manner: The minus pressure in the tube B holds the door C closed and through the tube E' exhausts the air in the cylinder 75 E² outside of the piston E therein, thereby holding the sliding gate or valve D in the open position shown in dotted lines in Fig. 1. The aperture e² in said cylinder serves to admit the outer air at atmospheric pressure and 80 cause this open position of the valve D. When a carrier passes beyond the valve D in the tube B, this latter being closed at its end by the door C, there is caused a compression of the air in the said tube between the carrier 85 and the door C, which would tend to arrest the carrier. Provision is made, however, for a partial equalization of this excess of pressure in front of the carrier by means of the by-pass F and its regulating-valve f. The excess still remaining passes through the tube 90 E' to the cylinder E² and there produces a pressure on the outer side of the piston E therein which equalizes or more than equalizes the atmospheric pressure on the other 95 side of the said piston. Since the inner end of the gate presents, as already set forth, a considerable area to the exhaust action in the tube B at this point, the gate or valve D will thereby be closed. This closure of the gate 100 D as soon as the carrier has passed the same relieves the carrier from the retarding influence of the exhaust and insures a sufficient remainder of momentum to cause the carrier

to strike against the hinged door C and, opening the same, pass out over it upon the way G' thereon provided and onto the ways G, where it is received by the attendant. The 5 spring c, while too weak to present an effectual resistance to the opening of the door C by the carrier, is of sufficient strength to return said door to its closed position after the carrier has passed out. The door C being 10 closed, the minus pressure in the tube B again returns the valve D to its original open position.

In the construction hereinbefore described 15 the gate or valve D is operated solely by the differences in pressure on the opposite sides of the piston thereof and by the action of the exhaust on the valve proper. This form is preferred where it is inadvisable to locate the gate and its operating mechanism vertically 20 relatively to the tube—as, for instance, in underground streetwork. Under circumstances admitting such a location of the valve, however, it will be seen that the same will be partly operated by gravity, and my invention 25 contemplates such a construction and operation.

I claim—

1. In a pneumatic-despatch-tube system, an exhausted terminal tube provided with a yielding delivery-door, in combination with a cylinder and piston, the cylinder connected on one side of the piston with the terminal tube near the delivery-door and on the other side thereof with the atmosphere, and a gate or valve operatively connected with said piston and adapted to close the receiving end of the terminal tube after the carrier has passed the same, substantially as described. 30

2. In a pneumatic-despatch-tube system, an exhausted terminal tube provided with a yielding delivery-door, in combination with a cylinder and piston, the cylinder connected on one side of the piston with the terminal tube near the delivery-door and on the other side thereof with the atmosphere, and a gate or valve in the receiving end of the terminal tube operatively connected with said piston and presenting a considerable area to be acted upon by the exhaust action of the tube, substantially as described. 40

LOUIS G. BOSTEDO.
